UNITED STATES PATENT OFFICE.

GEORGE H. JENKINS, OF CHICAGO, ILLINOIS.

HEATER FOR PRINTING-PRESSES.

1,236,178.

Specification of Letters Patent.

Patented Aug. 7, 1917.

Application filed May 12, 1916. Serial No. 97,149.

To all whom it may concern:

Be it known that I, GEORGE H. JENKINS, a citizen of the United States of America, and a resident of Chicago, county of Cook, 5 and State of Illinois, have invented certain new and useful Improvements in Heaters for Printing-Presses, of which the following is a specification.

The main objects of this invention are to 10 provide a heater for drying the ink on printed sheets as the sheets pass through the press, having improved means for controlling the operation of said heater; and to provide an improved connection of said 15 means to the mechanism which controls the operation of the press, whereby said means are automatically operated in unison with said mechanism and danger of fire is practically eliminated and a considerable saving 20 in fuel is effected.

An illustrated embodiment of this invention is shown in the accompanying drawings, in which—

Figure 1 is a perspective view in dotted 25 outline of a portion of the delivery end of a printing press, showing in full outline the heater and pilot light arranged thereon.

Fig. 2 is a side elevation in dotted outline of a printing press showing in full outline 30 the arrangement of the gas supply pipes, the valve by means of which the supply of gas is controlled and the controlling mechanism for the printing press connected to said valve.

Fig. 3 is an enlarged detail view taken on 35 the line A—A of Fig. 1, showing how the heater passes in under the paper as it leaves the delivery mechanism.

It is a well known practice in the printing business, to facilitate the drying of 40 printed matter by arranging a heater adjacent to the path of the paper at some point between its passing from the printing operation to the delivery table. This has 45 been most commonly accomplished by providing a gas heater 1 in the form of a tube 2 having a series of apertures 3 extending throughout the length thereof, arranged transversely across the press and below but 50 near the path of the paper.

In the construction shown in the drawings, the heater 1 is shown applied to a printing press of the "turn up" delivery type, in which case the pipe 2 is rigidly 55 secured to the reciprocating delivery carriage 4 directly in front of and slightly below the

clips 5 against which the sheet of paper is delivered as it leaves the printing cylinder. Thus, the heater is moved along under the sheet of paper (see Fig. 3) as the carriage 60 4 recedes therefrom, in allowing the sheet to settle on the delivery table 15. The shield 6 partially surrounds the pipe 2 so as to prevent direct contact of the flame with the paper. 65

A flexible hose connection 7 connects the burner 1 with the gas supply pipe 10, a valve 8 being arranged substantially as indicated, for the purpose of controlling the supply of gas to the burner. 70

Heretofore, the use of such a burner in this position has encountered two very serious objections, namely, excessive gas consumption and the danger of fire. An excessive gas consumption is occasioned by 75 reason of the full operation of the heater during intervals when the press is stopped for the purpose of attention to parts thereof, or to the replenishing of the paper supply on the feeding board. Ordinarily, the 80 operator does not feel justified in taking the time to shut off the gas when he stops the press and then relight it a few minutes later when starting up. The danger of fire is also frequently occasioned by the stopping 85 of the press with the burner directly under the sheet of paper, as will be apparent from Fig. 3.

Both of these objections are overcome by the applicant's invention, which comprises 90 a valve 9 located in the supply pipe 10 and arranged adjacent to the foot pedal 11 mounted on the operator's platform 14 and which controls the operation of the press. A link 12 connects the valve 9 with the foot 95 pedal 11 so that it is operated in synchronism therewith. Thus, when the press is stopped the gas is shut off from the burner and it matters not if the parts come to rest in the position shown in Fig. 3, there is no 100 danger of fire. Also the consumption of gas is discontinued as long as the press is idle.

A pilot light 13 is connected to the gas supply pipe 10 between the valve 9 and the source of supply, so that it is not affected 105 by the operation of the valve 9. This pilot light is located at one side of the press, adjacent to one end of the burner 1 and directly in the path thereof, so that gas issuing 110 from the apertures 3 after the valve 9 has been opened, will be ignited by the

flame of the pilot light 13, as the burner is moved past said light.

Although but one specific embodiment of this invention is herein shown and described, 5 it will be understood that the construction may be altered or details omitted without departing from the spirit of this invention as defined by the following claims:

I claim—

- 10 1. The combination with a printing press having mechanism for controlling the operation thereof, of a gas heater arranged adjacent to the path of paper passing through said press, a valve for controlling the supply 15 of gas to said heater, a connection between said valve and said mechanism whereby the shifting of said valve is controlled simultaneously with the operation of said press, and a pilot light arranged adjacent to said 20 heater and adapted to light said burner when said valve, after having been closed, is opened.
- 25 2. The combination with a printing press having mechanism for controlling the operation thereof, of a gas heater arranged adjacent and transverse to the path of paper passing through said press, a valve for con-

trolling the supply of gas to said heater, a connection between said valve and said mechanism whereby the shifting of said valve is controlled simultaneously with the operation of said press, and a pilot light arranged adjacent to one end of said heater and adapted to light said burner when said valve, after having been closed, is opened. 25

3. The combination with a printing press having a reciprocating delivery means and mechanism for controlling the operation of the press, of a gas heater mounted on said delivery means, a valve for controlling the supply of gas to said heater, a connection between said valve and said operating mechanism whereby the shifting of said valve is controlled simultaneously with the operation of said press, and a stationary pilot light arranged on said press adjacent to one end of said burner and in the path thereof, whereby it is adapted to light said heater when said valve, after having been closed, is opened. 40 45

Signed at Chicago this 10th day of May 1916.

GEORGE H. JENKINS.
